Inv. No. 1524,879
N. Rippenstein
by his Atty. T. F. Bourne

UNITED STATES PATENT OFFICE.

NICHOLAS RIPPENBEIN, OF JAMAICA, NEW YORK.

MERCANDISE CONTAINER.

Application filed December 30, 1922. Serial No. 609,805.

To all whom it may concern:

Be it known that I, NICHOLAS RIPPENBEIN, a citizen of the United States, and resident of Jamaica, Long Island, in the 5 county of Queens and State of New York, have invented certain new and useful Improvements in Merchandise Containers, of which the following is a specification.

My invention relates to the class of containers adapted to contain goods for storage 10 and transportation and to be opened to act as a support for the goods to display the same.

An object of my invention is to provide a 15 container comprising two main portions hinged together adapted to contain goods, said portions having corresponding sides provided with supporting edges arranged in such a manner that when the two portions 20 of the container are opened out and rested upon a flat support one of said portions will serve as a support for the goods to display them and the other portion will serve as a back or rest to retain the goods in exposed 25 position.

A further object of my invention is to provide a container of the character specified which will be simple and cheap to manufacture, and in which the goods may be inserted 30 at low cost of time and labor, the container requiring a minimum of material and which may be readily opened out for display purposes.

My invention comprises novel details of 35 improvement that will be more fully hereinafter set forth and then pointed out in the claims.

Reference is to be had to the accompanying drawings forming a part hereof, where- 40 in—

Fig. 1 is a perspective view of my im- 45 proved container in closed position to retain goods therein;

Fig. 2 is a perspective view illustrating the container opened in position to receive 50 goods;

Fig. 3 is a perspective view illustrating the container in display position supporting goods;

Fig. 4 is a perspective view showing the container collapsed for transportation;

Fig. 5 is a face view of a blank from which my improved container may be made;

Fig. 6 is a plan view of a blank for a 55 modification; and

Fig. 7 is a detail view of part of the container of Fig. 6 partly folded.

Similar numerals of reference indicate corresponding parts in the several views.

The container comprises two main re- 60cessed portions 1 and 2 which are hinged together so that when closed, as in Fig. 1, they form a box-like structure to contain goods, preferably of rectangular parallelopiped shape. Portion 1 of the container is 65 provided with an end wall 3 and a main wall 4 hinged thereto at the score line 5 and having sides 6 extending substantially at right angles to the wall 4 when the container is set up, said sides being foldable with respect to the wall 4 by means of the score lines 7. The sides 6 are to be secured to the wall 3 to retain the walls 3 and 4 substantially at right angles and so that the side of the portion 1 opposite the wall 4 will be 70 open, and for such purpose I provide the ends of wall 3 with wings 8 foldable along the score lines 9 of the blank, and I provide the sides 6 with score lines 11 acute to lines 7. When the walls 3 and 4 are set up sub- 75 substantially at right angles and the sides 6 are folded substantially at right angles to wall 4 the wings 8 will be folded to lap along the sides 6 and they may be glued together at the parts 10, as shown in Fig. 2. The outer edges of the wings 8 preferably substantially coincide with the score lines 11 when the parts are set up, whereby the sides 6 and the wings 8 with the wall 3 may be folded in- 80wardly against the wall 4 when the container is to be collapsed for storing and ship- 85ping, the walls 3 and 4 folding at the hinge 5.

The member 2 is provided with a plat- 90form or main wall 12 having sides 13 hinged thereto by means of the score lines 14, and an end wall 15 is hinged to the platform 12 at the score line 16, to be set up substantially at right angles to the platform wall. The end wall 15 is provided with side flaps 17 which are foldable along the score lines 18, and the sides 13 have score lines 13^a at acute angles to the score lines 14. When the portion 2 is to be set up the sides 13 and wall 15 will be folded substantially at right 95 angles to the platform 12, the wings 17 being folded toward the platform and lapping against the parts 13^b of sides 13, the wings 17 and the parts 13^b being glued together, 100 substantially as shown in Fig. 2. The wall 105 110

3 and platform 12 are hinged together at the score line 19. The adjacent longitudinal score lines 7, 9, 14 and 18 of the blank are virtually a continuous score line.

5 Means are provided to detachably secure the portions 1, 2 together when set up for use, for which purpose I have shown a flap 20 hinged to wall 15 at the score line 21, (Fig. 5), and provided with tongues 22 on 10 opposite sides to engage slits 23 in wall 4 to retain the parts together.

The outer edges 6^a of the sides 6 are at an acute angle to the sides of wall 4 along the score lines 7 and the outer edges 13^c of the 15 sides 13 are at an acute angle to the sides of platform 12 along the score lines 14, the edges 6^a and 13^c, when the blank is opened out flat, being substantially parallel on corresponding sides of the blank. As illustrated, the edges 6^a diverge from the end 20 4^a of wall 4 and the edges 13^c correspondingly diverge from the score line 19, so that when the container is set up and the portions 1 and 2 are closed the edges 6^a and 13^c will 25 oppose and correspond to produce a rectangular parallelopiped. The lines of junction of the edges 6^a, 13^c, when the container is set up, produce diagonals between the opposite corners at the sides of the container, 30 as illustrated in Fig. 1. The score lines 11 and 13^a of the sides 6 and 13 (Fig. 5), permit said sides to be folded inwardly upon wall 4 and platform 12 respectively, so that the folded portions 10 of the sides 6 will lie 35 between the walls 3 and 4 and the portions 13^b of the sides 13 will lie between the platform 12 and wall 15 when the container is collapsed or folded for transportation or 40 storage, (Fig. 4). When folded the flap 20 is extended along the platform 12.

Instead of providing score lines 13^a in the sides 13 so that the latter at said score lines may be folded between platform 12 and wall 15 the sides 13 may be left un-scored, as illustrated in Fig. 6, and score lines 15^a may be provided in wall 15 extending diagonally to a point from the ends of score line 16. When the wings 17 have been secured to the sides 13 to retain the platform 12 and its end wall at right angles, and it is desired to fold the container parts, the wall 15 may be folded along the score lines 15^a while the sides 13 are being folded against platform 12, so that the portions 55 15^b of wall 15 will overlie the main part of said wall, the adjacent ends of the sides 13 and the wings 17 folding inwardly at the score lines 18, (Figs. 5 and 6). The container may be finally folded as before described. In this instance I prefer to apply the flap 20 at the outer end of the platform 4 at the score line 21^a, and to provide the slits 23 in end wall 15 to receive the tongues 22, as in Fig. 6, to retain the container 65 closed when set up for use.

It will be understood that the triangular sides 13 are hinged at their apices adjacent to the bases of the triangular sides 6, at the outer edge of end wall 3, so that the rectangular formation may be produced when the 70 container is closed to retain goods therein, and whereby when the portions 1 and 2 are opened out, as in Fig. 3, the platform will be in front of wall 3, with the supporting edges 6^a, 13^c of the sides in a right line adapted to rest upon a flat surface. The goods A may be placed upon platform 12 for support in position for display, the wall 3, perpendicular to platform 12, serving as 75 a back rest for the goods. 80

Having now described my invention, what I claim is:

1. A foldable merchandise container comprising two recessed portions each having triangular sides and a pair of adjacent walls, said recessed portions being hinged together at the apices of the triangular sides of one of said portions, the triangular sides of one of said portions having score lines oblique to the two walls of said portion and extending from the inclined edges of said sides to adjacent ends of the edge joining the said two walls. 85

2. A merchandise container comprising two recessed portions hinged together, one of said portions having a platform wall and an end wall, said platform wall having hinged sides of substantially triangular shape having inclined supporting edges, the end wall having wings secured to said sides, the other portion having a main wall provided with triangular sides having edges inclined to said wall, the apices of the edges of said sides terminating at the hinge, the second named portion having an end wall provided with wings secured to the second named sides. 95

3. A merchandise container comprising two recessed portions hinged together, one of said portions having a platform wall and an end wall, said platform wall having hinged sides of substantially triangular shape having inclined supporting edges, the end wall having wings secured to said sides, the other portion having a main wall provided with triangular sides having edges inclined to said wall, the apices of the edges of said sides terminating at the hinge, the second named portion having an end wall provided with wings secured to the second named sides, one of said portions having a flap provided with a projection and the other portion having a slot to receive such projection. 110

4. A blank for a foldable merchandise container comprising a piece of flexible material having spaced longitudinally disposed score lines, a pair of spaced transverse score lines extending between the first named score lines, the blank having wings 12 13

extending from the space between said transverse score lines, said blank having pairs of sides extending from corresponding first named score lines on opposite sides of said transverse score lines, said sides having inclined outer edges, said edges on corresponding sides of the blank being substantially parallel and having their apices terminating at the first named score lines, said blank having another transverse score line adjacent to the bases of a pair of said sides beyond the first named transverse score lines, and wings extending from the blank beyond the second named transverse score line. ¹⁰

NICHOLAS RIPPENBEIN.
